In Sweden October 4, 1944

9 Claims. (Cl. 235—61)

1

The present application is a continuation-in-part of my co-pending application, Serial No. 619,706, filed October 1, 1945, now abandoned, entitled Time Computing Machines.

The present invention relates to a calculating machine for computing elapsed time between two points of time, that is computing differences of time and the total of such differences, such points of time being for example the beginning and the end of working hours as taken from time cards or other printed or written time records, and both the entrances and the results of the calculations being normally presented as hours and fractions of hours.

More particularly the invention refers to a time computing machine in which a counter for accumulating such differences of times is actuated in dependence of the distance over which an index travels between two points on a time scale when a wheel is rolling along a track, the wheel normally being out of engagement with the track but when in action being in engagement with the track for the time corresponding to the travel from one point on said scale to the other.

The chief object of the invention is to construct such a machine so as to render the computing operations reliable by locking the wheel in its position of rotation when not fully engaged by the track, and using a positive engagement of the wheel with the track when rolling along the same; and another object is to construct such machines so as to render the adding and subtracting operation involved, more easy and rapid.

A further object of the invention is to construct the time computing machine so that the entrances of the numerical information to be added or subtracted, may be made by the aid of a pointer movable along a fixed time scale, and the result can be obtained from an accumulating counter of common type.

These and other objects of the invention as well as features of the same will appear from the following specification and the claims.

Two embodiments of the invention are by way of example illustrated in the accompanying drawings, in which:

Figure 1 shows a perspective view of a time computing machine in accordance with one embodiment of the invention;

Figure 2 is a broken plan view showing the heart of the interior mechanism of the machine according to Fig. 1, on a greater scale; the wheel being axially displaceable in a carriage comprising two sections, the upper section of which is removed to show the internal means more clearly;

2

Figure 3 is a transverse vertical section on the line III—III in Fig. 2;

Figure 4 is a vertical cross-section on the line IV—IV in Fig. 2;

Figure 5 is a vertical cross-section on the line V—V in Fig. 2;

Figure 6 is a vertical cross section through a time computing machine according to another embodiment of the invention, the wheel being lifted to and fro engagement with the rack;

Figure 7 is a partial front view of the computing machine according to Fig. 6, the casing being partially cut away for showing details of the mechanism;

Figure 8 shows a top view of the carriage of the machine shown in Figs. 3 and 4; and

Figure 9 shows a time scale suitable for the machine.

Referring now to the drawings, 1 indicates an accumulating counter, having a number of totalizer or numeral wheels, indicating hours and fractions of hours. The counter may be of well-known construction and is not shown in detail here. It should be constructed both for additive and for subtractive operations. The counter 1 is stationary in the machine frame and is actuated in either direction of rotation by a shaft 2 rotatably journaled in the machine frame.

The shaft 2 is slotted at 3, and this slot is engaged by a spline in the hub 4a of a bevel gear wheel 4. The hub 4a of that wheel is journaled in a movable carriage 5 comprising two sections 5a, 5b screwed together. Thus, the wheel 4 is movable axially along the shaft 2, but the shaft 2 will be rotated when the wheel 4 rotates. This wheel meshes permanently with a second bevel gear wheel 6, which is also rotatably journaled in the carriage 5 by means of its hub 6a.

In the hub 6a of the wheel 6 a shaft 7 is displaceably splined and on that shaft a spur wheel 8 is secured. The wheel 8 is with its shaft 7 displaceable between two positions, viz. an inoperative position (Figs. 2 and 3) in which it is engaged by a locking stop tooth 19 secured to the top of the carriage 5, and an operative position (not illustrated in the drawing) in which the wheel 8 is in mesh with a toothed rack 9 stationary in the machine frame and parallel with the shaft 2. For displacing the wheel 8 between said two positions a coupling plate 16 attached to a runner or indicator member 10, is slidably mounted in the carriage 5, between the two sections 5a, 5b of the same, and is provided with a rectangular aperture 16c, within which the wheel 8 is located. The coupling plate 16 is fork-

shaped, having two lateral legs 16a, 16b sliding in corresponding grooves provided in the carriage 5. By means of a handle 12 secured to the runner 10, the operator can push the runner 10 and thus the coupling plate 16 inwards against the action of two springs 17 provided under tension between shoulders on said coupling plate and shoulders in the carriage 5, said springs being located in corresponding recesses in the carriage 5. The outward motion of the coupling plate 16, under the action of said springs, is limited by two stops 18 attached to the carriage 5, and the inward motion of the coupling plate is limited by engagement of the central portion of said plate with the body of the carriage 5.

The runner 10 has a window with an index line 15 cooperating with one or more scales 14 securely mounted on the casing 13. When the handle 12 is in its inoperative position, that is, when this handle is in its extreme outer position, as illustrated in Figs. 2 and 3, the wheel 8 does not mesh with the rack 9 but is engaged by the locking stop tooth 19, so that accidental rotation of the wheel 8 is prevented. Now the carriage 5 with its associated members can be moved axially along the shaft 2 without any actuation on the wheels 8, 6, 4 and the counter 1. For computing, the operator first moves the runner 10 and thus the carriage 5 laterally by means of the handle 12, still in its inoperative (undepressed) position, until the index line 15 coincides with that point or line of the scale 14, say 7.30 o'clock which marks the beginning of the work. Now the operator presses the handle 12 inwards and thus causes the wheel 8 to mesh with the rack 9, and then he moves the runner to the right, until the index line 15 coincides with that point of the time scale 14, say 16.00 (= 4 p. m.) which corresponds to the end of the work. When the runner thus has been moved between the points "7.30" and "16.00" of the scale, the wheels 8, 6, 4 rotate the shaft 2 so that the item 8½ is entered into the counter. Thus the counter directly shows the number of hours consumed for the work. If the work has been carried out during several periods of times separated by pauses, such periods are successively entered into the counter, which then shows the total. The counter may be cleared in well-known manner.

When the handle 12 is pressed inwards, the wheel 8 is not fully released from the stop tooth 19 until it has been brought into full engagement with the rack, and when moved outwards the wheel 8 is not fully released from the rack until it has been brought into full engagement with the stop tooth 19, the wheel 8 thus being locked against rotation when in all intermediate positions. Therefore, the wheel 8 will always be in such a position of rotation that its teeth are exactly in alignment with the spaces between the rack teeth. Of course, the smallest divisions on the scale must be of the same size as the relative distance of the teeth on the rack or be a small multiple of said distance.

In the embodiment illustrated in Figs. 3-8, the two accumulating counters 20 and 21 are arranged on the movable carriage 22. The carriage rolls on rollers 23 in rectilinear, stationary guides 24. On pins 25 in the side-walls of the carriage, a carrier 26 is rockably journaled. To the carrier 26 a handle or finger-piece 27 is secured, and a torsion or coil spring 28 serves to keep the carrier 26 with its handle in their uppermost position.

In bearings in the carrier 26 a shaft 29 is jour-

nalled, which in one end carries a spur gear wheel 30 and in the other end a bevel gear wheel 31 in permanent mesh with a second bevel gear wheel 32 on a shaft 33, rotatably journaled in the carriage 22. This shaft carries two actuator wheels 34, one for each of the counters 20 and 21. One of the counters 20, 21 shows the grand total, while the other shows the sub-total. The counters have individual clearing means in well-known manner.

When the operator presses down the handle 27 manually, the toothed wheel 39 comes into mesh with a stationary straight toothed rack 35 secured to the machine frame. On the shaft 29 also a dentated wheel 36 is secured which cooperates with a tooth 37 secured to the carriage 26. This tooth locks the wheel 36 and prevents the shaft 29 from rotating, as long as the handle 27 is not fully depressed. But as soon as the operator's finger depresses the handle 27 fully and the wheel 36 is liberated from the stop tooth 37, the wheel 30 is securely in mesh with the stationary rack 35 and rotates, when the carriage is moved laterally in its guides. Thus, when the carriage 26 is moved laterally, the wheel 30 is either locked or in full mesh with the rack 35. This prevents errors of calculation.

Thus, as will appear from Fig. 6, the stop wheel 36 is not fully released from the stop tooth 37 until the wheel 30 has fully engaged the rack 35, and the wheel 30 is not fully released from the rack 35 until the stop wheel 36 has fully engaged the stop tooth 37, the wheel 36 thus being locked against rotation in all intermediate positions. Therefore, the wheel 30 also in this embodiment will always be in such a position of rotation that its teeth are exactly in alignment with the spaces between the rack teeth. It should be understood that the stop wheel 36 must have the same number of teeth as has the wheel 30, and evidently the smallest division on the scale must also in this embodiment be of the same size as the relative distance of the teeth on the rack or be a small multiple of said distance.

The handle 27 extends through a longitudinal slot in the casing 38 of the machine, and through another slot in the casing an index 39 extends, showing the position of the carriage 26 on a time scale 40.

A preferred embodiment of this scale is illustrated in Fig. 9. The numerals appearing on this scale indicate the hours from 7 o'clock in the morning to 20.30 (= half past eight) in the evening. As is now usual in time printing clocks and similar time recording devices, the hours are subdivided in the decimal system. In the example illustrated in Fig. 9, it is assumed that the work is stopped for meals between 11 and 12 and also between 16.5 (= half past four p. m.) and 17. In order to automatically deduce these pauses in time computations by means of the machine, the points for "11" and "12" are coinciding on the scale, and also the points for "16.5" and "17." Thus, when a work has been carried out between 10 o'clock and 13 o'clock with a pause of one hour for lunch, only two hours are registered in the accumulators 20 and 21, when the index 39 is moved from "10" to "13" on the scale 40.

In the casing 38 there is a long window 41 for rendering it possible to read the counters 20, 21 in any position of the carriage 26.

The mode of operation is as follows:

When the time total is to be computed from a time record, such as a printed card from a time control machine, showing the points of time, on

which the various operations of the work began and ended, the operator first moves the carriage 26 by means of the handle 27 (then undepressed) to the position, in which the index 39 points on that line of the scale 40 which corresponds to the point of time at which the work began. He now depresses the handle 27 fully so that the wheel 30 comes into mesh with the rack 35 and the dented wheel 36 is liberated from the stop tooth 37, and then he moves the carriage to the right (in Fig. 4), until the index reaches that line of the scale 40 which corresponds to the point of time at which the work ended. Consequently the wheel 30 is rotated an angle proportional to the time consumed and into the counters 20, 21 a value (an item) is entered proportional to that time. If several periods of time have been consumed for one work, they may be entered in a similar manner. The counter 20 may be cleared after each single operation, while the grand total of the operations is cumulated in the counter 21.

The scale 40 is detachable so that a scale having another division to suit other conditions may be substituted for it.

It may also be mentioned that the rack 35 and the scale 40 parallel with it may be slightly curved. If so, the radius of curvature should be at least 20 cm. and the scale should cover at most

$$150^\circ = \frac{150}{360} \text{ of a revolution}$$

By this the operator will be able to move the handle 27 while resting his elbow on the table at the center of the curvature.

The machine may be used for computing the difference of time between two points of time specifically stated, and also the sum total of such differences. It is useful for calculating wages, charges to be debited to a customer for work carried out, timing as used in scientific industrial management etc.

An ordinary time scale (without interruptions for meals and other pauses) may be arranged along the scale 40, or may be substituted for it. An ordinary scale and an "interrupted" scale may be engraved on the same metal strip like 40 (Fig. 6).

Having thus described the invention, I claim:

1. A time computing machine for computing differences of times and the totals of such differences, comprising, in combination, a stationary scale divided in units of time, an index movable along the scale, at least one accumulating counter for accumulating differences of time and an actuator for said counter, a toothed rack mounted stationarily in parallel with the scale and having its teeth arranged at distances corresponding to the divisions of said scale, a toothed gear wheel for cooperation with said rack, a movement transmission from the rack to the actuator, in which transmission said toothed wheel is included, a carriage movable along said rack and scale, which carriage supports said index as well as at least the toothed wheel of said movement transmission, coupling means mounted in said carriage for interrupting said movement transmission when the carriage with index is to be moved along the scale and no entry in the counter is to be made, but holding said transmission operative when the carriage with index is moved along the scale between two points of time, the difference of which is to be entered into the counter, and locking means for preventing rotation of said toothed wheel when said

movement transmission is interrupted, and allowing such rotation only when said movement transmission is complete.

2. A time computing machine for computing differences of times and the totals of such differences, comprising, in combination, a stationary scale divided in units of time, an index movable along the scale, at least one accumulating counter for accumulating differences of time and an actuator for said counter, a toothed rack mounted stationarily in parallel with the scale and having its teeth arranged at distances corresponding to the divisions of said scale, a toothed gear wheel for cooperation with said rack, a movement transmission from the rack to the actuator, in which transmission said toothed wheel is included, a carriage movable along said rack and scale, which carriage supports said index as well as at least the toothed wheel of said movement transmission, coupling means mounted in said carriage for moving said toothed wheel out of mesh with said rack when the carriage with index is to be moved along the scale and no entry in the counter is to be made, but holding said toothed wheel in mesh with said rack when the carriage with index is moved along the scale between two points of time, the differences of which is to be entered into the counter, and locking means for preventing rotation of said toothed wheel when not fully in mesh with said rack.

3. A time computing machine for computing differences of times and the totals of such differences, comprising, in combination, a stationary scale divided in units of time, an index movable along the scale, at least one accumulating counter for accumulating differences of time and an actuator for said counter, a toothed rack mounted stationarily in parallel with the scale and having its teeth arranged at distances corresponding to the divisions of said scale, a toothed gear wheel for cooperation with said rack, a movement transmission from the rack to the actuator, in which transmission said toothed wheel is included, a carriage movable along said rack and scale, which carriage supports said index as well as said movement transmission together with counter actuator, coupling means mounted in said carriage for interrupting said movement transmission when the carriage with index is to be moved along the scale and no entry in the counter is to be made, but holding said transmission operative when the carriage with index is moved along the scale between two points of time, the difference of which is to be entered into the counter, and locking means for preventing rotation of said toothed wheel when said movement transmission is interrupted, and allowing such rotation only when said movement transmission is complete.

4. A time computing machine for computing differences of times and the totals of such differences, comprising, in combination, a stationary scale divided in units of time, an index movable along the scale, an accumulating counter for accumulating differences of time and an actuator for said counter, a toothed rack mounted stationarily in parallel with the scale and having its teeth arranged at distances corresponding to the divisions of said scale, a toothed gear wheel for cooperation with said rack, a movement transmission from the rack to the actuator, in which transmission said toothed wheel is included, a carriage movable along said rack and scale, which carriage supports said index, a rocker

mounted in said carriage and supporting said toothed wheel with associated parts for lifting said toothed wheel out of engagement with said rack when the carriage with index is to be moved along the scale and no entry is to be made in the counter, but holding said toothed wheel in mesh with said rack when the carriage with index is moved along the scale between two points of time, the difference of which is to be entered into the counter, and locking means for preventing rotation of said toothed wheel when not fully engaged in the rack.

5. A time computing machine as claimed in claim 4, wherein said locking means comprises a stationary stop tooth for preventing rotation of said toothed wheel already at the beginning of the disengagement of the toothed wheel from the rack.

6. A time computing machine as claimed in claim 4, wherein said toothed wheel is firmly connected with a dentated wheel for engagement with a stop tooth as soon as the toothed wheel begins to move out of mesh with the rack.

7. A time computing machine as claimed in claim 3, wherein two counters are provided, one for sub-totals and the other for the grand total of the computing operations.

8. A time computing machine as claimed in claim 2, wherein said toothed wheel is axially slideable out of and into mesh with said rack.

9. A time computing machine as claimed in claim 2, wherein a handle is provided for actuating said coupling means and moving said carriage.
